UNITED STATES PATENT OFFICE

155,627

DESIGN FOR A TABLE LIGHTER

Paul Pouliot, Montreal, Quebec, Canada, assignor to Presto Lighters Limited, Montreal, Quebec, Canada

Application August 3, 1949, Serial No. 4,268

Term of patent 7 years

(Cl. D48—27)

To all whom it may concern:

Be it known that I, Paul Pouliot, a citizen of Canada, residing at 1901 Moreau Street, city of Montreal, Province of Quebec, Canada, have invented a new, original, and ornamental Design for Table Lighter, of which the following is a specification, reference being had to the accompanying drawing, forming part thereof. The

I claim:

The ornamental design for a table lighter, as shown.

PAUL POULIOT.
